Primary Examiner — John Windmuller*Assistant Examiner* — Benjamin M Weeks(74) *Attorney, Agent, or Firm* — Greenblum & Bernstein,
P.L.C.(57) **CLAIM**

We claim the ornamental design for a pedal board, as shown and described.

DESCRIPTION

FIG. 1 is a perspective view of a pedal board;
 FIG. 2 illustrates a top view of FIG. 1;
 FIG. 3 illustrates a bottom view of FIG. 1;
 FIG. 4 illustrates a back view of FIG. 1;
 FIG. 5 illustrates a front view of FIG. 1;
 FIG. 6 illustrates a right side view of FIG. 1; and,
 FIG. 7 illustrates a left side view of FIG. 1.
 The broken lines in the figures depict portions of the pedal board that are not part of the claimed design.
